Primary Examiner — Keli L Hill(74) *Attorney, Agent, or Firm* — Plumsea Law Goup, LLC(57) **CLAIM**

The ornamental design for a loudspeaker, as shown and described.

DESCRIPTION

FIG. 1 is a perspective view of a loudspeaker showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is an end elevational view of one end thereof; and, FIG. 7 is an end elevational view of the opposite end thereof. The broken line showings form no part of the claimed design.
